CLAIM

The ornamental design for a distribution point unit with surface ornamentation, as shown and described.

DESCRIPTION

FIG. 1 is a front perspective view of a distribution point unit with surface ornamentation showing our new design;

FIG. 2 is a bottom view thereof;

FIG. 3 is a top view thereof;

FIG. 4 is a left view thereof;

FIG. 5 is a right view thereof;

FIG. 6 is a front view thereof; and,

FIG. 7 is a rear view thereof.

The dot-dash broken lines immediately adjacent to the claim represent the bounds of the claim, while all other broken lines are directed to environment. The broken lines form no part of the claimed design.
